(57) **CLAIM**

The ornamental design for a hall effect sensor holder, as shown and described.

DESCRIPTION

FIG. 1 is a top perspective view of a hall effect sensor holder showing my new design;

FIG. 2 is a bottom perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof, the right side elevational view being a mirror image of the left; and, FIG. 8 is a perspective view thereof at an installed position on an electric motor.

The broken line showing of the environment is for illustrative purposes only and forms no part of the claimed design.
